UNITED STATES PATENT OFFICE.

PETER CELESTIN HARBOUR, OF CHICAGO, ILLINOIS.

DESIGN FOR A PIN.

SPECIFICATION forming part of Design No. 17,006, dated November 30, 1886.

Application filed May 22, 1885. Serial No. 166,403. Term of patent 7 years.

To all whom it may concern:

Be it known that I, PETER CELESTIN HARBOUR, a citizen of the United States, residing at Chicago, in the county of Cook and State 5 of Illinois, have invented and produced a new and original Design for Pins, of which the following is a specification, reference being had to the accompanying drawing, in which the figure is a face view of the pin as made according to my design.

My pin is circular in its general contour, and has around its edge a border, *a*, consisting of a series of triangular figures arranged with the apex of the triangles outward. Within 15 in this border is the figure of a cross, as at *b*,

and across the lower portion of the same is the figure of a deer, *c*, having grasses *d* represented beneath and in front and rear of it, as shown.

Having thus fully described my pin, what I claim, and desire to secure by Letters Patent, 20 is—

The design for a pin, consisting of the circular face provided with the border *a*, the cross *b* within the same, and a deer, *c*, across the lower portion of said cross, substantially as 25 shown and described.

PETER CELESTIN HARBOUR.
